UNITED STATES PATENT OFFICE.

JOHN W. FRIES, OF WINSTON SALEM, NORTH CAROLINA.

APPARATUS FOR HUMIDIFYING AND CLEANSING AIR.

SPECIFICATION forming part of Letters Patent No. 772,655, dated October 18, 1904.

Application filed March 4, 1903. Serial No. 146,182. (No model.)

To all whom it may concern.

Be it known that I, JOHN W. FRIES, of Winston Salem, county of Forsyth, State of North Carolina, have invented an Improvement in 5
Apparatus for Humidifying and Cleansing Air, of which the following is a specification.

My invention has reference to apparatus for humidifying and cleansing air; and it consists of certain improvements fully set forth 10 in the following specification and shown in the accompanying drawings, which form a part thereof.

The object of my invention is twofold—namely, to regulate the humidity of the air 15 within any confined space, such as a large room, factory, or auditorium, and to collect and remove all dust and floating particles of dirt or deleterious matters from the air, thereby purifying and freshening it.

20 My object is also to chemically treat the air for disinfecting purposes when such treatment is necessary.

In many instances it is important to add 25 moisture to an otherwise dry atmosphere to increase the humidity, whether it be for facilitating manufacturing operations or for hygienic reasons and comfort. Thus, for instance, in textile mills when the atmosphere is too dry—*i. e.*, its hygrometric condition

30 too low in humidity—the cotton becomes under the ordinary manipulation electrified, with the result that the fiber ends stand out and give to it a more or less fuzzy appearance. This condition interferes materially in the 35 textile operations of producing cloth. By my invention the humidity may be increased to the proper degree to secure such hygrometric conditions as will overcome this abnormal tendency of the yarn to become electrified.

40 In many mills the atmosphere becomes so heavily laden with floating particles of dust that, aside from being dangerous on account of fire, it is most objectionable and injurious to the workmen and girls employed in operating the machines. By my invention all of 45 the objectionable floating particles may be extracted from the air and the latter brought to a fresh and healthful condition.

In carrying out my invention I provide 50 means to act upon air and a supply of water whereby the air carries the water in suspension

to a circulating device which imparts to it a centrifugal and rotary action for the purpose of spreading the water out upon the interior surface of a cylindrical shell and for causing 55 the air to take a spiral path over the surface of said film of water, whereby it becomes humidified to the proper degree. When this is done, the air and water are caused to pass through a discharge opening and guide which 60 collects the water and removes it and also separates the humidified air and directs it into the room. This same operation purifies the air, because the action of the moisture is such that it causes the floating particles to separate 65 from the air and become absorbed by the water, and by which they are conveyed away. In those cases where disinfecting is necessary the air in passing to or through the apparatus is caused to pass over suitable chemicals— 70 such as calcium chlorid, caustic soda, &c. It is thus seen that the humidified air is not only brought to the right condition for the proper working of the cotton, but it is washed or cleansed and brought to a condition 75 most healthful and pleasant to the operatives. It is evident that these same conditions are most desirable in large halls and auditoriums or places where people may congregate, and hence my invention is adapted to such purposes. Where it is desired to simply eliminate excessive moisture, such as exists on very 80 humid days in summer, the supply of water may be omitted and hygroscopic chemicals only employed. 85

In carrying out my invention in its preferred form I employ a tubular case having a central inlet at one, or open, end and a circulating-fan at the other and closed end. Into the central portion of the tubular casing air 90 is sucked by the action of the fan and given an outward and reversed movement, so as to travel backward through the tubular case and escape at the end most distant from the fan. Combined with the said parts I provide a nozzle for supplying a spray of water or other fluid within the central portion of the case in front of the fan, whereby the fluid is intermingled with the circulating air and caused by centrifugal action to spread out upon the 95 inner surface of the tubular case in a thin film, and the air assumes a spiral and pro-

gressing motion over this film of water and absorbs the necessary amount of moisture and is also subjected to the desired cleansing operation. At the discharge end of the case it 5 is provided with means for permitting the air to escape into the room, whereas the water is collected into a suitable funnel and discharged through a drain-pipe.

Where chemicals are to be used for disinfecting or other purpose, I place them within 10 an open vessel supported in the path of the inflowing air, so that it is caused to pass over such chemicals in reaching the fan.

My invention also embodies details of construction which, together with the above general features, will be better understood by reference to the drawings, in which—

Figure 1 is a longitudinal sectional elevation of an apparatus embodying my invention. Fig. 2 is a cross-section of same on line 20 2 2 looking toward the circulating-fan end, and Fig. 3 is a cross-section on line 3 3 looking toward the discharge end.

A is a cast-iron head and has a central opening G, formed by a rearwardly-extending circular flange. It is also provided with a downwardly-extending portion N, terminating in a funnel P, connecting with a discharge or waste pipe p. Fitted to the outer flange B 25 of the head A is a cylindrical or tubular case or shell D, of sheet metal, the opposite end thereof being closed by a cast-metal cap E, flanged, as at e, to receive the end of the said sheet-metal shell. Bolts d are employed to 30 clamp the head A and cap E upon the tubular shell D. A conical inwardly-directed flange F is arranged within the case D adjacent to the head A, the smaller and open end f being directed inward toward the fan H. 35 This fan is so designed that it draws in the air through the aperture G and central part of the tubular case D and discharges it radially over the fan and tangentially therefrom under centrifugal action against the inner surface 40 of the case D. The fan, as shown, consists of a closed back H' and a series of radial blades J, extending forward from the back. These blades may be connected at the front part by an annular ring-piece H² to 45 form apertures or passages I between the blades J near the hub of the fan for better directing the movement of the air. This fan is rotated by a shaft K, journaled in a suitable frame L and driven by a hand-wheel M, or, if desired, by any of the well-known means for driving fans now in commercial use—such, for example, as the direct application of an electric motor. The frame L is secured to the cap E and is adapted for 50 attachment to the ceiling or other convenient place. The head A is also provided with a support L', likewise adapted for attachment to the ceiling. By means of these frames L and L', the entire apparatus may be suspended 55 in suitable position.

Arranged at the front entrance G is a water-nozzle R, which preferably extends inward close to the hub of the fan, by which water or fluid may be sprayed or otherwise admitted, and thereby be drawn into the apparatus by the incoming rush of air passing to the fan H.

The air passing through the head A takes up the water, and both are forced outwardly against the inner surface of the case D and 75 outwardly discharged through the aperture C into the discharge guide or flue O, which is preferably a curved downwardly-arranged flanged sheet terminating in the funnel P at the bottom for carrying off the water. It is 80 open on the side at O' for allowing the humidified air to escape into the room.

The opening C in the cylindrical shell D is quite large, and one edge of said opening is continued in the curved and flanged plate O, 85 which is gradually reduced in width until its smaller end enters the funnel P, as shown. In this way the rotary currents of air and water traveling along the interior of the shell pass outward upon the curved plate D, with 90 the result that the water enters the funnel P and the air freely escapes into the atmosphere. The pipe p drains the dirty water from the apparatus and leads it to the sewer.

The conical flange F properly guides the 95 rotary currents of air and water and directs them into the opening C. The flange F prevents the water climbing to the flange G and being thrown back with the incoming air, and in this way the air is prevented from becoming overladen with moisture. Once the separation of the air and water takes place on the inner surface of the wheel D it is not desired that they shall commingle again. It is of course evident that this conical flange F may be cast integral with the head A and that the tubular flange G may be dispensed with and the opening f in the flange F relied upon for entering air.

There is an opening f' between the space F' between the flange G and the conical flange F, which opens into the discharge-aperture C, so as to allow the escape of any water which may find access into said space without again commingling with the air.

The operation may be described as follows: The fan being in motion and air circulating as indicated by the arrows, water is admitted by the nozzle R in the requisite quantity to provide the humidity desired and also the water necessary to produce the washing operation and film over which the air is forced. This admixture of air and moisture is drawn through the central portion of the case to the center of the fan G with considerable force and driven outward under the centrifugal action of the said fan. This fan is so shaped that it causes the moisture-laden air to flow backward adjacent to the inner face of the case or shell D with great rotary and centrifugal force.

gal action, creating, in effect, spiral currents with horizontal axis. By this means the water, owing to its greater specific gravity, is caused to spread over the interior surface of the shell D in a thin film, and under the rotary and forward movement of the air said water film is caused to gradually travel forward toward the head A. In this manner the air is caused to move over a surface of water and press upon it with considerable force, and thereby take up the proper degree of moisture in the shortest period of time to secure the desired humidity. The centrifugal action of the air in its rotary motion continues to assist in holding the water against the interior surface of the shell and to keep it from settling to the bottom thereof. It thus maintains the water film in the most effective condition and causes it to gradually travel toward the discharge end, while at the same time inducing it to take up any floating particles which the air may contain. When the air and water reach the head conical flange F, the rotary action continues until they escape through the opening C, the air escaping into the atmosphere and the water passing over the discharge guide-plate O and into the waste-pipe p. The air passes tangentially through the open side O' of the guide-plate O into the room. The conical flange F prevents the rotary currents of air passing out of entrance G interfering with the incoming air or the flow of water to said opening G. The degree of humidity of the air so treated may be determined by the use of any well-known type of hygrometer arranged close to the apparatus.

The admixture of the water and air in the first instance, coupled with the frictional treatment between the two at and after leaving the fan, insures the thorough washing and cleansing of the air and clears it of all floating particles of deleterious matters.

In those cases where the air is to be treated chemically for disinfecting purposes or for other reasons, such as the removal of carbonic acid or removing excessive moisture, I employ a vessel S, (indicated in dotted lines,) which may be of any suitable form in which the chemicals—such as calcium chlorid, caustic soda, or sulfurous acid—may be placed. This vessel may be supported upon guide-ribs g on the inner face of the tubular flange G very much like a drawer. In practice the vessels may be sealed cans, and for use the top be torn off; so as to expose the contents. Any other method of introducing the chemicals may be resorted to, if desired.

It is evident that I may modify the general arrangement and details of the apparatus in many ways without departing from the spirit of the invention. Hence I do not confine myself to the minor details shown.

Having now described my invention, what

I claim as new, and desire to secure by Letters Patent, is—

1. In an apparatus for cleansing and humidifying air, the combination of a horizontal tubular shell closed at one end and having the other provided with a central aperture surrounded by an annular channel open at the bottom, a circulating-fan arranged close to the closed end of the shell for creating a centrifugal and rotary motion to the air, a nozzle for supplying a fluid close to the center of the fan, and means leading from the open portion of the channel for conveying off the fluid and allowing the air to escape.

2. In an apparatus for cleansing and humidifying air, the combination of a horizontal tubular shell closed at one end and having the other provided with a central aperture surrounded by an annular channel open at the bottom, a circulating-fan arranged close to the closed end of the shell for creating a centrifugal and rotary motion to the air, a nozzle for supplying a fluid close to the center of the fan, and means leading from the open portion of the channel for conveying off the fluid and allowing the air to escape consisting of a curved flanged sheet O tangentially connected with the edge of the opening from the channel at the bottom of the shell.

3. In an apparatus for cleansing and humidifying air, the combination of a horizontal tubular shell closed at one end and having the other provided with a central aperture surrounded by an annular channel open at the bottom and also provided with upwardly-extending supports or brackets for attaching the apparatus to the ceiling, a circulating-fan arranged close to the closed end of the shell for creating a centrifugal and rotary motion to the air, a nozzle for supplying a fluid close to the center of the fan, and means leading from the open aperture of the channel and extending downward for conveying off the fluid and allowing the air to escape.

4. In an apparatus for cleaning and humidifying air, the combination of a cylindrical shell closed at one end and provided with an aperture through its lower part at its other end, a conical flange F secured within the shell at its open end forming a central opening f, a draining device secured to the aperture to collect the fluid and allow the air to escape, a circulating-fan arranged at the closed end of the case for imparting a rotary and traveling motion to the air and fluid, and a nozzle for supplying fluid within the shell close to the center of the fan.

In testimony of which invention I have hereunto set my hand.

JOHN W. FRIES.
